DESIGN.

J. W. HANCOCK.

FACE OF A CEILING ELECTRIC LIGHT REFLECTOR.

APPLICATION FILED JAN. 15, 1921.

59,892.

Patented Dec. 6, 1921.

Inventor:

John W. Hancock,

*by Spear Middleton Donaldson Hall
Atty's.*

UNITED STATES PATENT OFFICE.

JOHN W. HANCOCK, OF DENVER, COLORADO.

DESIGN FOR THE FACE OF A CEILING ELECTRIC-LIGHT REFLECTOR.

59,892.

Specification for Design.

Patented Dec. 6, 1921.

Application filed January 15, 1921. Serial No. 437,598. Term of patent 7 years.

To all whom it may concern:

Be it known that I, JOHN W. HANCOCK, a citizen of the United States, residing at Denver, Colorado, have invented a new, original, and ornamental Design for the Face of a Ceiling Electric-Light Reflector, of which the following is a specification, reference being had to the accompanying drawing, forming a part hereof.

The figure is a plan view of the reflecting face showing my new design.

I claim—

The ornamental design for the face of a ceiling electric light reflector, as shown.

JOHN W. HANCOCK.
